by

G. C. Cleau Attorney

UNITED STATES PATENT OFFICE.

CHARLES LAWRENCE STOKES, OF LOS ANGELES, CALIFORNIA.

LIQUID-FEED SYSTEM.

Application filed July 25, 1917, Serial No. 182,640. Renewed October 10, 1922. Serial No. 593,659.

To all whom it may concern:

Be it known that I, CHARLES LAWRENCE STOKES, a citizen of the United States, residing at Los Angeles, in the county of Los Angeles and State of California, have invented certain new and useful Improvements in Liquid-Feed Systems, of which the following is a specification.

This invention relates to systems for feeding or lifting liquids, and particularly to systems operated by the suction of an internal combustion motor.

It is an object of this invention to provide improved valve devices to be used in the operation of the apparatus and also to provide a simplified construction thereof.

In my Patents Nos. 1,230,537-1,230,596, and 1,230,832, issued June 19, 1917, I have explained and laid claims generally to mechanism for lifting liquid fuel from a low level tank to a high level reservoir to feed the carburetor embodying admission of atmosphere to the lift line and the subsequent drawing of air into the engine intake. It is an object of this invention to make improvements upon said prior devices particularly in the manner of the valve constructions.

In such liquid feed systems as herein described the liquid is lifted by suction to a reservoir, the suction therein being applied intermittently and atmospheric pressure being admitted to the surface of the liquid in the reservoir during the periods between suction impulses so that the liquid in the reservoir may feed by gravity to the carburetor.

It is an object of this invention to provide improved valve means for cutting off the application of suction and admitting atmosphere approximately at the same time to the liquid in the reservoir, and it is also an object to increase the lifting efficiency of the device by providing such valve means. It is also an object to increase the dumping or discharge efficiency of the device by providing improved valve construction in the discharge pipe.

Referring to the drawings:

Fig. 1, is a section of the reservoir in detail.

Fig. 2, is a section of the springs and levers along the dotted line 2^a-2^a.

Fig. 3, is a diagram showing the relative positions and connections of the different parts of the system.

In the drawings the feed tank 1 is shown at a lower level than the carburetor 25, which is of the usual float feed type, and which is below the level of the service reservoir 3. The fuel tank 1, is of the usual type used in an automobile at the rear end, and is provided with a filler cap 27, which is open to atmosphere through the vent 28. This cap may be unattached to the pipe 2 so that it may slide upwardly along the latter as it is removed for filling. A pipe or communication 2 joins the tank 1 with the reservoir 3. This pipe 2 reaches about to the bottom of tank 1 and is provided with a small air hole 29 above the liquid level in the tank 1, which is supplied with air through the vent 28, which is of relatively large diameter. I do not claim anything on the filler cap construction, this being well explained and claimed in my prior and co-pending applications S. N. 175,533 filed June 18th, 1917, and S. N. 179,621 filed July 10th, 1917. The upper end of pipe 2 is led to a fitting 16 in the bottom of the reservoir 3, which fitting is suitably fastened to the reservoir 3. The stand-pipe 35 is a continuation of the pipe 2, and may be part of it. The pipe 35 constitutes a guide for the float 7, as will be hereinafter described. The reservoir 3, contains the float and valve mechanism for operation and is fitted with a cover 13, which is suitably fastened to it so as to render it air-tight except as hereinafter provided.

A fitting 4 is fastened to the cover 13 and is suitably bored to receive a valve 6, which is freely movable therein. The valve 6 is always open to atmosphere at one end and contains an air passage 5, which is at times closed by the wall 30, and at other times is open to atmosphere throughout. It also has an enlarged portion 39 which engages the seat 40 when suction is to be cut off. The lower portion of valve 5 is encircled by a light spring 14 and is slidably engaged in the top of the baffle plate 8, being held therein by a cotter pin 9, or other suitable means. The baffle plate 8 is firmly fixed on the top of the tube 34 which is placed in the center of the float 7, and the

tube 34 is freely movable on the outside of the tube 35. The baffle 8 is for the purpose of preventing undue turbulence in the reservoir 3 when fuel is sucked up from the tank 1 through the pipe 2, and tubes 34, and 35, through the slots or orifices 41 and 42 provided therein.

The baffle 8 also provides means for holding in place the arms 32 and 33 which constitute levers for moving the springs 10 and 11 into and out of tension, upon the rise and fall of the float 7, one end of the springs 10 and 11 being engaged with the levers 32 and 33 and the other end being engaged with the rods, 12 and 12a, which are fastened into the fitting 4 or the cover 13 if 4 is made integral with 13. 15 is a spring encircling the tube 34 and is freely movable between the end of lever 17 and the bottom of float 7. 17 is a lever pivoted at 18 and connected with the discharge valve 19 to positively seat the latter upon fall of the float 7. The discharge valve 19 is of greater weight than the lever 17 and is housed in the fitting 20, which has a valve seat 36, a plug 21 containing a groove to guide the valve 19 and discharge pipe 23 feeding the carburetor 25.

Suction is applied to the reservoir 3 through pipe 22 which may be fitted to the intake pipe 24 of an internal combustion motor at a point preferably between the throttle 26 and the engine intake.

In the drawings selected for illustration, the reservoir is shown in a position where discharge has been completed, the float being down, the reservoir having suction applied to it and the discharge valve being closed.

I now explain the operation of the system:

Partial vacuum being applied to the interior of the reservoir 3, through the pipe 22, the passages 38, 37 and 31, liquid is sucked from the tank 1 through the pipes 2 and 35, passing through the slots 41 and 42 and striking the baffle 8 is deflected to the top of the float 7 and thence to the bottom of the reservoir. The air which passes with the liquid through the hole 29 is carried on and consumed in the engine charge.

Liquid thus fills the reservoir to a predetermined point which is such that the buoyancy of the float 7 is sufficient to overcome the tension of the springs 10 and 11 induced by the levers 32 and 33, and when this point is reached the head of the float, which in this case is the top of baffle 8, moves from a point below the plane of a line drawn through the points of connection of springs 10 and 11 with the rods 12 and 12a, to a point above it, thus carrying the valve 6 to its seat 40, and cutting off suction. During this movement the outer ends of the levers slide along the under side of

the cover until the raising of the inner ends of the levers brings the intermediate portions of the levers above the points of anchorage of the springs and the springs then tend to swing the outer ends of the levers downwardly instead of pressing them up against the cover. The levers thus exert an upward rather than a downward thrust to the tube 24 and the valve 6 connected thereto. At the same time the spring 14 is put in compression and the air passage 5 which has been closed by the wall 30, is now open to atmosphere throughout, and thus the reservoir is opened to atmosphere through the passage 5 and the hole 31 in the skirt of the sleeve 30. The float being in its upper position the spring 15 is extended and arranged to be such that it will not touch the float 7 at any point where the top of the float is above the plane before referred to, but it will keep the valve 19 closed until the float "jumps". The weight of the float thus being taken off the spring 15, the lever 17 and the valve 19, the valve 19 has sufficient weight to fall and the reservoir being opened to atmosphere the liquid therein passes by gravity through the pipe 23 to the carburetor 25.

Upon the completion of discharge of the reservoir, the reverse of the above described action takes place. The liquid being withdrawn from the float a predetermined point is reached where the weight of the float is such that it is sufficient to overcome the tension of the springs 10 and 11 induced by the levers 32, 33 and the head of the float, which in this case, is the top of baffle 8, moves from a point above the plane of a line drawn through the points of engagement of springs 10, 11 to a point below said plane thus carrying the valve 6 from its seat 40 opening the reservoir to suction. At the same time the air passage 5 is closed to atmosphere by slidably engaging the wall 30, and the weight of the float, after passing the aforesaid plane is transmitted through the spring 15, lever 17 to the valve 19 which is raised to its seat 36. The spring 14 is also extended, its purpose and length being such that it serves to keep the valve 5 on its seat until the head of the float moves past aforesaid plane.

It will thus be apparent from the above description that a simplified and improved valve is usable performing two functions, that of cutting off suction and admitting atmosphere to the reservoir at approximately the same time, the action of the springs 10, 11 aiding this approximation. At the same time the actuation of valve 19 is also made positive in its seating, it being well known that a "suction operated valve" sometimes lags in its seating especially under a low vacuum.

The construction is simplified by using

the upper end of lift pipe 2 as a guide for the float 7, and it is apparent that there can be many changes made in the detail of construction shown without interfering with the spirit of my invention; or the scope thereof as defined in the claims. Modifications will readily suggest themselves to one skilled in the art.

Having described my preferred form of invention, I claim:

1. In a device of the class described, a reservoir having a cover, a pipe to feed liquid thereto, a float, means to alternately open and close said reservoir to suction and atmosphere actuated by the float; and spring means to control the movement of the float, said means embodying two levers engaging opposite sides of the head of the float and springs, each fixed at one end to its corresponding lever and at the other end to anchorage fixed to said cover.

2. A vacuum fuel feed reservoir having a valve casing, carried by one wall thereof and including a valve seat intermediate of its ends, a suction port above said seat, communication below said seat with the interior of said reservoir, an annular wall below said seat, a valve provided with a corresponding seat intermediate of its ends and having a passage extending lengthwise therethrough opening at one end to the atmosphere and the other end at a point below the last mentioned valve seat, a float within said reservoir, and connections between said float and said valve for raising said valve to shut off suction at said valve seat and raise the lower end of said passage above said annular wall or close the lower end of said passage by said annular wall and permit suction past said valve seat.

3. A vacuum liquid fuel reservoir, including a vertically guided float, a valve connected thereto and movable in axial alignment therewith, spring means connecting said float and said valve, permitting of a limited relative axial movement and normally tending to hold them separated to the maximum extent, and spring means tending to lift said float to limiting position and compressing said first mentioned spring means to hold said valve to its seat when said float is raised past a predetermined position.

4. A liquid fuel feed reservoir having a valve, a float connected thereto, a pair of levers extending in opposite directions and

each having its inner end connected to said float, and a pair of springs each having one end anchored to said reservoir and the opposite end connected to the outer end of its corresponding lever, the intermediate portion of said levers being moved past the point of anchorage during a raising or lowering of the float.

5. A liquid fuel feed reservoir having a liquid inlet pipe extending upwardly through the bottom thereof, a float guided on said pipe, and an annular baffle connected to said float and disposed above the open upper end of the inlet pipe for deflecting downwardly and outwardly the liquid entering the reservoir through said pipe.

6. A liquid fuel feed reservoir having an inlet pipe extending upwardly through the bottom thereof, and having an outlet at its upper end, a float slideable on said pipe and normally disposed below said outlet, means connected to the upper end of the float for controlling the communication between said reservoir and suction or the atmosphere, and an outlet valve in the bottom of the reservoir and controlled by the movement of the float.

7. A liquid fuel feed reservoir having a float therein, a vertically disposed guide along which said float operates, an outlet valve in the bottom of the reservoir, a coil spring encircling said guide below said float, and a member connected to said outlet valve and serving as a seat for said spring, for closing the valve upon the movement of said float to its lowermost position.

8. A liquid fuel feed reservoir having a float therein, a vertically disposed guide along which said float operates, an outlet valve in the bottom of the reservoir, a coil spring encircling said guide below said float, and a member connected to said outlet valve and serving as a seat for said spring, for closing the valve upon the movement of said float to its lowermost position, said valve opening by gravity when said spring is relieved of the action of said float upon the movement of the latter to its uppermost position.

In testimony whereof I affix my signature in presence of two witnesses.
